UNITED STATES PATENT OFFICE.

CHRISTIAN SCHOEN, OF NEWARK, NEW JERSEY.

EMBROIDERY-FRAME.

1,088,301.

Specification of Letters Patent. Patented Feb. 24, 1914.

Application filed August 16, 1913. Serial No. 785,067.

To all whom it may concern:

Be it known that I, CHRISTIAN SCHOEN, a citizen of the United States, residing at Newark, in the county of Essex and State of New Jersey, have invented certain new and useful Improvements in Embroidery-Frames; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention has reference, generally, to improvements in embroidery frames, and, the invention relates, more particularly, to a novel work-holding frame for use with embroidery machines, with a view of providing an easily manipulated embroidery frame, in which several pieces of the work to be embroidered can be readily placed and secured in a perfectly stretched and taut relation, so that the parts of the several stretched pieces of work may be perfectly and simultaneously embroidered upon by the needles of the embroidery machine, when the frame, with the work in position therein, has been placed in the machine.

The invention has for its principal objects to provide a simply-constructed and easily manipulated embroidery frame in which articles of wear, such as handkerchiefs, and the like, can be readily secured with ease in perfectly stretched or taut relation, and are positively clamped in their positions in the frame, so that the articles to be embroidered upon will not work loose or sag during the operation of embroidering when the frame is placed in the embroidery machine.

Other objects of this invention not at this time more particularly enumerated will be clearly understood from the following detailed description of the present invention.

With the various objects of the present invention in view, the invention consists, primarily, in the novel embroidery frame hereinafter set forth; and, the invention consists, furthermore, in the novel arrangements and combinations of the several devices and parts, as well as in the details of the construction of the same, all of which will be more fully described in detail in the following specification, and then finally embodied in the clauses of the claims which are

appended to and which form an essential part of the said specification.

The invention is clearly illustrated in the accompanying drawings, in which:—

Figure 1 is a plan view of a fragmentary portion of an embroidery frame made according to and embodying the principles of this invention, showing in connection therewith, a number of handkerchiefs properly arranged and clamped in position in the frame, ready to be placed in the embroidery machine. Fig. 2 is a detail plan view of a portion of the embroidery frame; said view being made on a larger scale, the handkerchief being omitted, so as to show more particularly the general construction of the work-clamping mechanism. Fig. 3 is a transverse vertical section, taken on line 3—3 in said Fig. 2; Fig. 4 is a transverse vertical section, taken on line 4—4 in said Fig. 2, the spring-controlled latch-bolt, however, being shown in side elevation; Fig. 5 is a transverse vertical section, taken on line 5—5 in said Fig. 2, with certain parts represented in side elevation; and Fig. 6 is a longitudinal vertical section, said section being taken on line 6—6 in said Fig. 2, with the work-clamping bar represented in side elevation.

Similar characters of reference are employed in all of the above described views, to indicate corresponding parts.

Referring now to the several figures of the drawings, the reference-characters 1 and 2 indicate a pair of bars of the embroidery frame, which may be made of wood, or any other suitable material. At suitable intervals, the bar is provided in its upper face with a plurality of transversely extending grooves or depressions, as 3, any number of such grooves or depressions being employed, according to the length of the embroidery frame. In a similar manner, and corresponding in number to and in alinement with said grooves or depressions 3, the bar 2 is provided in its upper face with transversely extending grooves or depressions, as 4. The reference-character 5 indicates a number of U-shaped or channel-bars, corresponding in number to the number of grooves or depressions 3 and 4, and said channel-bars having their respective end-portsions suitably arranged in the alined grooves or depressions 3 and 4 of the respective bars 1 and 2, and permanently se-

cured therein by means of screws 6 and 7, as shown in Fig. 6 of the drawings. It will be understood, however, that any other suitable means may be employed for securing the end-portions of the channel bars 5 to the frame-bars 1 and 2. From an inspection of said Fig. 6 of the drawings, it will be seen, that each channel-bar, when viewed from the top, is made with the suitably wide end-portions 8 and 9, and the intermediate narrow clamping portion 10, formed by the side-walls of the respective portions 8 and 9, and 10, and the side-walls of the said portion 10 being integrally united at their respective ends with the side-walls of the parts 8 and 9. The end-portion 9 of each channel-bar is also preferably made to taper toward a pair of perforated pintle or pivot-pin receiving end-members 11 in which are arranged the ends of a pintle or pivot-pin 12 which extends across the space between the said end-members 11. Pivotally mounted upon each pintle or pivot-pin 12 is a clamping-bar or member, as 13, each clamping bar or member being preferably made of suitable flat metal, and each clamping bar or member being adapted to be lowered into the channel of its respective channel-bar 5, and being of such length, that the end-portion 14 of the bar or member 13 will project from the end-portion 8 of the channel-bar, substantially as shown in Figs. 1, 2 and 6 of the drawings, and the said end-portion 14 of the bar or member 13 being formed with a suitable fingerpiece, as 15. As will be noticed from an inspection of said Fig. 2 of the drawings, that portion between the walls of the clamping portion 10 of the channel-bar 5 is approximately equal to the width of the clamping bar or member 13, so as to produce at this point a perfect clamping effect, the bar or rod 13 being furthermore provided at this point and upon its lower surface with a supporting member or shoe, as 16, which serves also as a fulcrum for pressing the inserted material upon the inner surface of the channel-bar 5, and permitting of a resilient action of the end-portion 14 of the bar member 13, so that when it is sprung under the nosing of the latch-bolt, to be presently described, the resilient action and tendency to move in an upward direction will positively retain the clamping bar or member 13 in its locked and clamping relation within the said channel-bar 5, as will be clearly seen from an inspection more particularly of Figs. 2, 3, 4 and 6 of the drawings.

The said latch-bolt device for retaining the clamping bar or member 13 in its lowered position, consists, essentially, of a main body-plate 17 secured by means of screws 18, or other suitable fastening means, upon the upper face of the frame-bar 1, to one side of the channel or groove 3 and the end-portion 14 of the bar or member 13, as shown in

Figs. 1, 2 and 4, the said body-plate being provided with a pair of perforated ears or lugs, as 19 and 20, in which is slidably mounted a latch-bolt 21. Upon one end, this latch-bolt is provided with a suitable fingerpiece, as 22, and upon its other end it is chamfered or tapered off, as at 23, to provide a holding or locking nosing 24. A coiled spring 25 is mounted upon that portion of the bolt-body, located between a pin 26, which is connected with said bolt-body, and the perforated lug 19, the tendency of said spring normally being to move the latch-bolt in the direction of the arrow α in Fig. 4 of the drawings, so that the chamfered or tapered part 23 of the nosing 24 will project directly over the channeled end-portion 8 of the channel-bar 5, in the manner illustrated. It will be evident, that when a raised clamping bar 13 is lowered, the lower edge-portion 27 of the bar is brought down upon said chamfered or tapered part 23, and during its further downward movement, the latch-bolt is caused to slide in the opposite direction from that indicated by said arrow α , until the said bar or member 13 has been moved past the nosing 24, when the action of the spring 25 once more returns the latch-bolt into its normal initial position, with the nosing 24 sprung over the upper edge of the clamping bar or member 13, so as to positively retain said bar or member 13, with its shoe 16 resting in its holding or clamping relation upon the material placed between the portion 10 of the channel-bar 5 and said shoe, as will be clearly understood.

To release the clamping bar or member 13 all that is necessary is to pull the latch-bolt 21 back, by means of its fingerpiece, so as to remove the nosing 24 from its holding engagement with the clamping bar or member 13, when the resilient action of said bar or member will spring the same slightly in an upward direction, and the bar or member 13 can then be raised by means of its finger-piece 15, for the removal of the previously clamped piece of work.

In Fig. 1 of the drawings, I have shown one arrangement of a number of such work-holding or clamping devices, and a number of suitably folded handkerchiefs 28 in their clamped relation in the embroidery frame, the corner-portion 29 of each handkerchief, the parts 30 of which are to be embroidered being clamped by means of suitable clamping devices which are suitably secured, in the desired positions, upon the upper surface of the frame-bar 2, in the positions indicated in Figs. 1 and 2 of the drawings. One form of such clamping devices is represented in Figs. 1, 2 and 5 of the drawings, and each clamping device consists, essentially, of a pair of members, as 31 and 32, arranged upon each other, as in Fig. 5, and having angularly bent and perforated parts,

as 33 and 34, which extend down the side 35 of the frame-bar 2, and are secured to said bar 2 by means of screws 36, or any other suitable fastening means. Upon their opposite end-positions, and extending slightly down the side 37 of said frame-bar 2, the said members 31 and 32 are respectively provided with suitable clamping or holding jaws, as 38 and 39. The upper clamping member 31 is made from suitable spring-metal, and is also formed with an opening 40 in which is rotatably disposed the hub 42 of a tightening lever 41, the latter being provided with a suitable fingerpiece, as 43, and a binding member, as 44, which is slidably disposed upon the upper surface of said member 31, to force the jaw 38 into its clamping relation with the jaw 39, when the lever 41 is in the position indicated in Figs. 2 and 5 of the drawings. That the clamping lever 41 may be suitably rotated, its perforated hub 42 is suitably disposed upon a screw-bolt 45 formed with a head 46, said bolt 43 extending through the frame-piece 2, and being secured in place by means of a nut 47 which is screwed upon the screw-threaded shank of said pin or bolt extending from the lower face of the said frame-bar 2, as shown. It will be understood, that any other suitable means for rotatably securing the tightening lever 41 in its operative position may be employed, and in lieu of the form of clamping device just described and illustrated in the accompanying drawings, any other suitably constructed clamping device may be employed.

The manipulation of the several devices and parts for positively stretching and securing the work, which is to be embroidered, in the embroidery frame will be clearly understood from the foregoing description and from an inspection of the several figures of the drawings, and any further detailed description of the same is, therefore, deemed unnecessary.

I am fully aware that changes may be made in the general arrangements and combinations of the various devices and parts, as well as in the details of the construction of the same, without departing from the scope of the present invention as set forth in the foregoing specification and as defined in the clauses of the claims which are appended thereto. Hence, I do not limit my present invention to the exact arrangements and combinations of the several devices and parts, as described in the said specification, nor do I confine myself to the exact details of the construction of the said parts, as illustrated in the accompanying drawings.

I claim:—

1. An embroidery frame comprising frame-bars, said bars being provided with transverse grooves, channel-bars having

their respective end-portions fixed in the grooves of the frame-bars, a clamping bar within each channel-bar, said clamping bar being pivotally connected at its one end-portion with said channel-bar, and means connected with one of said frame-bars, consisting of a main body-plate secured upon said frame-bar, bearing-portions connected with said plate, and a spring-controlled latch-bolt slidably mounted in said bearing-portions and in engagement with the other end-portion of said clamping bar for retaining said clamping-bar in its clamped relation within the channel-bar. 75

2. An embroidery frame comprising frame-bars, said bars being provided with transverse grooves, channel-bars having their respective end-portions fixed in the grooves of the frame-bars, a clamping bar within each channel-bar, said clamping bar being pivotally connected at its one end-portion with said channel-bar, and means connected with one of said frame-bars, consisting of a main body-plate secured upon said frame-bar, bearing-portions connected with said plate, and a spring-controlled latch-bolt slidably mounted in said bearing-portions and in engagement with the other end-portion of said clamping bar for retaining said clamping bar in its clamped relation within the channel-bar, and a finger-piece upon said latch-bolt for withdrawing it from its engagement with the clamping bar. 95

3. An embroidery frame comprising frame-bars, said bars being provided with transverse grooves, channel-bars having their respective end-portions fixed in the grooves of the frame-bars, said channel-bars comprising channeled portions of greater width at the end-portions of said bars, and intermediate narrow clamping portions, all formed by the side walls of the bars, said side-walls having inwardly extending wall-portions integrally united with the extremities of the said side-walls, a clamping bar within each channel-bar, said clamping bar being pivotally connected at its one end-portion with the channel-bar, a clamping shoe connected with and extending downwardly from the lower edge of said clamping bar, and means connected with one of said frame-bars and in engagement with the other end-portion of said clamping bar for retaining said clamping bar in its clamped relation within the channel-bar. 115

4. An embroidery frame comprising frame-bars, said bars being provided with transverse grooves, channel-bars having their respective end-portions fixed in the grooves of the frame-bars, a clamping bar within each channel-bar, said clamping bar being pivotally connected at its one end-portion with said channel-bar, a clamping shoe connected with and extending downwardly 130

from the lower edge of said clamping bar, and means connected with one of said frame-bars, consisting of a main body-plate secured upon said frame-bar, bearing-portions connected with said plate, and a spring-controlled latch-bolt slidably mounted in said bearing-portions and in engagement with the other end-portion of said clamping bar for retaining said clamping bar in its clamped relation within the channel-bar.

5. An embroidery frame comprising frame-bars, said bars being provided with transverse grooves, channel-bars having their respective end-portions fixed in the grooves of the frame-bars, a clamping bar within each channel-bar, said clamping bar being pivotally connected at its one end-portion with said channel-bar, a clamping shoe connected with and extending downwardly from the lower edge of said clamping bar, and means connected with one of said frame-bars, consisting of a main body-plate secured upon said frame-bar, bearing-portions connected with said plate, and a spring-controlled latch-bolt slidably mounted in said bearing-portions and in engagement with the other end-portion of said clamping bar for retaining said clamping bar in its clamped relation within the channel-bar, and a finger-piece upon said latch-bolt for withdrawing it from its engagement with the clamping bar.

6. An embroidery frame comprising frame-bars, said bars being provided with transverse grooves, channel-bars having their respective end-portions fixed in the grooves of the frame-bars, each channel-bar comprising wide end-portion and a narrow clamping portion intermediate of said wide end-portions, a clamping bar within each channel-bar, said clamping bar being pivotally connected at its one end-portion with said channel-bar, a clamping shoe connected with and extending downwardly from the lower edge of said clamping bar into the narrow clamping portion of the channel-bar, and means connected with one of said frame-bars, consisting of a main body-plate secured upon said frame-bar, bearing-portions connected with said plate, and a spring-controlled latch-bolt slidably mounted in said bearing-portions and in engagement with the other end-portion of said clamping bar for retaining said clamping bar in its clamped relation within the channel-bar.

7. An embroidery frame comprising frame-bars, said bars being provided with transverse grooves, channel-bars having their respective end-portions fixed in the grooves of the frame-bars, each channel-bar comprising wide end-portion and a narrow clamping portion intermediate of said wide end-portions, a clamping bar within each channel-bar, said clamping bar being pivot-

ally connected at its one end-portion with said channel-bar, a clamping shoe connected with and extending downwardly from the lower edge of said clamping bar into the narrow clamping portion of the channel-bar, and means connected with one of said frame-bars, consisting of a main body-plate secured upon said frame-bar, bearing-portions connected with said plate, and a spring-controlled latch-bolt slidably mounted in said bearing-portions and in engagement with the other end-portion of said clamping bar for retaining said clamping bar in its clamped relation within the channel-bar, and a fingerpiece upon said latch-bolt for withdrawing it from its engagement with the clamping bar.

8. An embroidery frame comprising frame-bars, said bars being provided with transverse grooves, channel-bars having their respective end-portions fixed in the grooves of the frame-bars, the channeled portions of said bars being of greater width at the end-portions of the bars, the intermediate narrow parts of said bars forming clamping portions, a clamping bar within each channel-bar, said clamping bar being pivotally connected at its one end-portion with said channel-bar, and means connected with one of said frame-bars and in engagement with the other end-portion of said clamping bar for retaining said clamping bar in its clamped relation within the channel-bar, combined with an auxiliary clamping means attached to another frame-bar for clamping a portion of the article to be embroidered, consisting of a pair of clamping plates provided with clamping jaws, and a rotary clamping lever for bringing said jaws into their clamped holding relation, and the said intermediate narrow clamping portions of the channel bars being such that only part of each clamping bar is actively engaged for clamping.

9. An embroidery frame comprising frame-bars, said bars being provided with transverse grooves, channel-bars having their respective end-portions fixed in the grooves of the frame-bars, a clamping bar within each channel-bar, said clamping bar being pivotally connected at its one end-portion with said channel-bar, and means connected with one of said frame-bars, consisting of a main body-plate secured upon said frame-bar, bearing-portions connected with said plate, and a spring-controlled latch-bolt slidably mounted in said bearing-portions and in engagement with the other end-portion of said clamping bar for retaining said clamping bar in its clamped relation within the channel-bar, combined with an auxiliary clamping means attached to another frame-bar for clamping a portion of the article to be embroidered, consisting of a pair of clamping plates provided with clamping plates 120

jaws, and a rotary clamping lever for bringing said jaws into their clamped holding relation.

10. An embroidery frame comprising 5 frame-bars, said bars being provided with transverse grooves, channel-bars having their respective end-portions fixed in the grooves of the frame-bars, a clamping bar within each channel-bar, said clamping bar 10 being pivotally connected at its one end-portion with said channel-bar, and means connected with one of said frame-bars, consisting of a main body-plate secured upon said frame-bar, bearing-portions connected with 15 said plate, and a spring-controlled latch-bolt slidably mounted in said bearing-portions and in engagement with the other end-portion of said clamping bar for retaining said clamping bar in its clamped relation within 20 the channel-bar, and a fingerpiece upon said latch-bolt for withdrawing it from its engagement with the clamping bar, combined with an auxiliary clamping means attached to another frame-bar for clamping a portion 25 of the article to be embroidered, consisting of a pair of clamping plates provided with clamping jaws, and a rotary clamping lever for bringing said jaws into their clamped holding relation.

30 11. An embroidery frame comprising frame-bars, said bars being provided with transverse grooves, channel-bars having their respective end-portions fixed in the grooves of the frame-bars, the channeled 35 portions of said bars being of greater width at the end-portions of the bars, the intermediate narrow parts of said bars forming clamping portions, a clamping bar within each channel-bar, said clamping bar being 40 pivotally connected at its one end-portion with said channel-bar, a clamping shoe connected with and extending downwardly from the lower edge of said clamping bar, and means connected with one of said frame- 45 bars and in engagement with the other end-portion of said clamping bar for retaining said clamping bar in its clamped relation within the channel-bar, combined with an auxiliary clamping means attached to

50 another frame-bar for clamping a portion of the article to be embroidered, consisting of a pair of clamping plates provided with clamping jaws, and a rotary clamping lever for bringing said jaws into their clamped holding relation, and the said intermediate 55 narrow clamping portions of the channel bars being such that only part of each clamping bar is actively engaged for clamping.

60 12. An embroidery frame comprising frame-bars, said bars being provided with transverse grooves, channel-bars having their respective end-portions fixed in the grooves of the frame-bars, a clamping bar 65 within each channel-bar, said clamping bar

being pivotally connected at its one end-portion with said channel-bar, a clamping shoe connected with and extending downwardly from the lower edge of said clamping bar, and means connected with one of said frame-bars, consisting of a main body-plate secured upon said frame-bar, bearing-portions connected with said plate, and a spring-controlled latch-bolt slidably mounted in said bearing-portions and in engagement with the other end-portion of said clamping bar for retaining said clamping bar in its clamped relation within the channel-bar, combined with an auxiliary clamping means attached to another frame-bar for clamping a portion of the article to be embroidered, consisting of a pair of clamping plates provided with clamping jaws, and a rotary clamping lever for bringing said jaws into their clamped holding relation.

13. An embroidery frame comprising frame-bars, said bars being provided with transverse grooves, channel-bars having their respective end-portions fixed in the grooves of the frame-bars, a clamping bar 90 within each channel-bar, said clamping bar being pivotally connected at its one end-portion with said channel-bar, a clamping shoe connected with and extending downwardly from the lower edge of said clamping bar, and means connected with one of said frame-bars, consisting of a main body-plate secured upon said frame-bar, bearing-portions connected with said plate, and a spring-controlled latch-bolt slidably mounted in said bearing-portions and in engagement with the other end-portion of said clamping bar for retaining said clamping bar in its clamped relation within the channel-bar, and a fingerpiece upon said latch-bolt for withdrawing it from its engagement with the clamping bar, combined with an auxiliary clamping means attached to another frame-bar for clamping a portion of the article to be embroidered, consisting of a pair of clamping plates provided with clamping jaws, and a rotary clamping lever for bringing said jaws into their clamped holding relation.

14. An embroidery frame comprising frame-bars, said bars being provided with transverse grooves, channel-bars having their respective end-portions fixed in the grooves of the frame-bars, each channel-bar comprising wide end-portion and a narrow 115 clamping portion intermediate of said wide end-portions, a clamping bar within each channel-bar, said clamping bar being pivotally connected at its one end-portion with said channel-bar, a clamping shoe connected with and extending downwardly from the lower edge of said clamping bar into the narrow clamping portion of the channel-bar, and means connected with one of said frame-bars, and in engagement with the 120

130

other end-portion of said clamping bar for retaining said clamping bar in its clamped relation within the channel-bar, combined with an auxiliary clamping means attached 5 to another frame-bar for clamping a portion of the article to be embroidered, consisting of a pair of clamping plates provided with clamping jaws, and a rotary clamping lever for bringing said jaws into their clamped 10 holding relation.

15. An embroidery frame comprising frame-bars, said bars being provided with transverse grooves, channel-bars having their respective end-portions fixed in the 15 grooves of the frame-bars, each channel-bar comprising wide end-portion and a narrow clamping portion intermediate of said wide end-portions, a clamping bar within each channel-bar, said clamping bar being pivotally connected at its one end-portion with said channel-bar, a clamping shoe connected with and extending downwardly from the lower edge of said clamping bar into the narrow clamping portion of the channel-bar, 20 and means connected with one of said frame-bars, consisting of a main body-plate secured upon said frame-bar, bearing portions connected with said plate, and a spring-controlled latch-bolt slidably mounted in said 25 bearing portions and in engagement with the other end-portion of said clamping bar for retaining said clamping bar in its clamped relation within the channel-bar, combined with an auxiliary clamping means attached 30 to another frame bar for clamping a portion of the article to be embroidered, consisting of a pair of clamping plates provided with clamping jaws, and a rotary clamping lever for bringing said jaws into their clamped 35 holding relation.

40. 16. An embroidery frame comprising frame-bars, said bars being provided with transverse grooves, channel-bars having their respective end-portions fixed in the 45 grooves of the frame-bars, each channel-bar comprising wide end-portion and a narrow clamping portion intermediate of said wide end-portions, a clamping bar within each channel-bar, said clamping bar being pivotally connected at its one end-portion with said channel-bar, a clamping shoe connected with and extending downwardly from the lower edge of said clamping bar into the narrow clamping portion of the channel-bar, 50 and means connected with one of said frame-bars, consisting of a main body-plate se-

cured upon said frame-bar, bearing-portions connected with said plate, and a spring-controlled latch-bolt slidably mounted in said bearing-portions and in engagement with the other end-portion of said clamping bar for retaining said clamping bar in its clamped relation within the channel-bar, and a fingerpiece upon said latch-bolt for withdrawing it from its engagement 60 with the clamping bar, combined with an auxiliary clamping means attached to another frame-bar for clamping a portion of the article to be embroidered, consisting of a pair of clamping plates provided with 65 clamping jaws, and a rotary clamping lever for bringing said jaws into their clamped holding relation.

17. The herein described channel-bar for an embroidery frame comprising channelled 75 portions of greater width at the end-portions of the bar and an intermediate narrow clamping portion, all formed by the side-walls of the bar, said side-walls having inwardly extending wall-portions integrally 80 united with the extremities of the said side-walls, combined with a clamping bar pivoted in said channel-bar, and the intermediate narrow clamping portion of the channel-bar being such that only part of the 85 clamping bar is actively engaged for clamping.

18. The herein described channel-bar for an embroidery frame comprising channelled 90 portions of greater width at the end-portions of the bar and an intermediate narrow clamping portion, all formed by the side-walls of the bar, said side-walls having inwardly extending wall-portions integrally 95 united with the extremities of the said side-walls, combined with a clamping bar pivoted in said channel-bar, said clamping bar having a clamping shoe extending downwardly therefrom and into said narrow clamping portion of the channel-bar, and 100 said intermediate narrow clamping portion of the channel-bar being such that only part of the clamping bar is actively engaged for clamping.

In testimony, that I claim the invention 105 set forth above I have hereunto set my hand this 15th day of August, 1913.

CHRISTIAN SCHOEN.
